UNITED STATES PATENT OFFICE.

HENRY WRAY, OF PAWTUCKET, RHODE ISLAND, ASSIGNOR TO THE CLARK THREAD COMPANY, OF NEWARK, NEW JERSEY, A CORPORATION OF NEW JERSEY.

THREAD-CUTTING DEVICE FOR SKEINING MACHINES.

Application filed March 8, 1928. Serial No. 259,965.

The invention relates to an improvement in thread cutting devices for skein winding and binding machines of the type shown in the patent to Max O. Clauss No. 1,401,519, 5 dated December 27, 1921.

Machines of the type shown in this patent comprise a series of skein holders, means for winding thread or yarn upon the skein holders successively to form the skeins, means 10 for moving the skein holders to present them successively to the skein forming means, means for placing a binder on each skein and means for cutting the thread extending from one skein to the next successive skein. 15 The object of the present invention is to provide a machine of this type with additional and improved means for cutting the thread at any desired point between two successive skeins. To this end the invention consists 20 in the improved thread cutting device hereinafter fully described and particularly pointed out in the appended claims.

In the accompanying drawings illustrating the preferred form of the invention, Fig. 1 25 is a top plan, partly in section, of so much of the machine shown in said patent as is necessary to illustrate the application of the improved thread cutting device of the present invention thereto; Fig. 2 is a front elevation of the improved thread cutting device with the associated parts of the skein winding and binding machine; Fig. 3 is a sectional plan taken on the line 3—3 of Fig. 2, and showing the thread cutting blades in open 30 position; Fig. 4 is a sectional plan taken on the line 4—4 of Fig. 2, and showing the thread cutting blades in closed position; and Fig. 5 is an enlarged side elevation of the 35 thread cutting blades and of their associated parts, and showing their relation to two adjacent and successive skeins.

The skeins are wound on a series of skein 40 holders 10, 11, 12 mounted on a rotatable shaft 13 journaled in the frame 14 of the machine. As each skein is wound the shaft 13 is turned in a clockwise direction to present the next skein holder to the skein winding means. As indicated in Fig. 1 the skein 45 15 on skein holder 10 has already been wound and the skein 16 supported on the holder 11 is undergoing the winding operation. On the completion of the winding of skein 16 skein 50 holder 11 will be moved to the position of skein holder 10 and skein holder 12 will move 55 into the position of skein holder 11 to receive

the threads forming the new skein. When the uppermost skein holder on which is supported the skein being wound moves to its next successive position, that occupied by skein holder 10, the thread from the completed skein is extended to and constitutes the first winding of the new skein. This thread is indicated in Fig. 1 at 17. Before the skeins are removed from the skein holders it is necessary to part this thread. The 60 thread parting means shown in the said patent parts this thread at substantially the middle point 18, and this thread parting means is indicated generally at 19. While the mechanism 19 and its actuating means are operating to sever the thread 17, other means of the machine of said patent, indicated generally at 20 and 21, operate to place a binder 22 (Fig. 5) upon the strands of thread 23 extending between the side arms 24 of the 65 skein holder 10.

The thread parting and binding means of 70 said patent are carried by an arm 25 pivoted at the point 26. The arm 25 carries on its underside a roll 28 which travels in a cam 75 path 29 formed in the periphery of the drum 30 mounted on the shaft 31. The part 20 of the skein binding means is provided with a rack 32 engaged by a toothed segment 33 mounted on a vertically arranged shaft 34 80 journaled in the boss 35 supported on the underside of the arm 25. Mounted on the shaft 34 beneath the segment 33 is a pinion 85 36 which meshes with the toothed end 37 of an arm 38 pivoted at the point 39 on the 90 arm 25. On its other end the arm 38 carries a roll 40 adapted to be engaged by the cam surface 41 to turn the arm 38 in a counter-clockwise direction to rotate the shaft 34 in a clockwise direction and cause the member 95 20 to move axially during the skein binding operation. A spring 42 returns the arm 38 to normal position. The swinging of the arm 25 under the action of the cam path 29 carries the arm 38 and the parts associated 100 with it into and out of operative or skein binding position, all as fully described in said patent.

After the thread parting means 19 have 105 severed the thread 17 extending from skein 15 to skein 16 and the skein binding means 20 and 21 have operated to place a binder 22 on the threads extending between the arms 24 of the skein holder 10, the shaft 13 is actuated to advance the skein holders through an 110

other step of their travel. Skeins 15 and 16 now occupy the relative positions indicated at 43 and 44, respectively, in Fig. 5. The upper half of the thread 17, which is now severed, is indicated at 45 and the lower half is indicated at 46. It will be understood that the distance separating the skein holders 10 and 11 in the positions which they occupy in Fig. 1 is about double the distance separating them in the positions they occupy in Fig. 5. Hence the thread ends 45 and 46 each are about equal the distance separating the skein holders 10 and 11 in Fig. 5. The improved thread cutting device of the present invention operates to sever the thread end 46 relatively close to the skein holder 10.

The improved thread cutting device comprises a fixed cutting blade 48 and a movable cutting blade 49. The blade 48 is secured to the lower, horizontal part 50 of a bracket 51, the vertically arranged part 52 of which is secured by the screws 53 to the depending part 54 of the forward end of the arm 25. The part 52 of the bracket 51 is provided with a longitudinal slot 55 which permits bracket 51 and the blades carried by it to be adjusted vertically. The movable blade 49 is pivotally mounted at the point 57 on the underside of the fixed blade 48. A spring 58 holds the blades in proper cutting relation. On its rear end the blade 49 is provided with an arm 59 offset at right angles with the blade. On its free end the arm 59 carries an upstanding roll 60 loosely received within a slot 61 formed longitudinally in the arm 62 secured by the screw 63 to the lower end of the shaft 34. While the arm 25 is in its inoperative position, as shown in Fig. 1, the parts associated with the movable cutter 59 occupy the positions shown in Figs. 1 and 3, with the blade 49 held separated from the blade 48. When, however, the arm 25 has been swung in a counter-clockwise direction on its pivot point 26 for the operation of parting the thread 17 and applying a binder on the skein held on the skein holder 10, the open blades 48 and 49 are carried to a position to engage and cut the upstanding end 46 of the skein 43, as shown in Fig. 5. The turning of the shaft 34 during the binding operation causes the arm 62 to be turned in a clockwise direction and thereby swing the arm 59 and the blade 49 on the pivot point 57, closing the blade 49 upon the blade 48 to sever the thread end 46 relatively close to the skein 43.

To assure a proper cutting action by the blades 48 and 49 upon the thread end 46 I provide means for holding the upper part of the thread end 46 during the cutting action. The thread holding means consist of a support in the form of a bracket 65 secured by one of the screws 53 to the front face of the vertical part 52 of the bracket 51. A spring member 66 cooperates with the bracket to hold the thread end 46. The spring member

66 is provided with a spiral section 67 which loosely embraces the lower end of the shaft 34, the free end of the spiral entering a collar 68 secured to the shaft 34. As the arm 25 swings in the counter-clockwise direction to bring the thread parting mechanism 19 and the binding parts 20 and 21 into operative position, and the open cutter blades 48 and 49 are thereby brought into cutting relation with the upstanding thread end 46, the bracket 65 is moved against the upper part of the thread end 46. Then as the shaft 34 is turned in the clockwise direction for the binding operation and the movable cutter blade 49 is closed upon the fixed cutter blade 48, the spring member 66 is moved toward the bracket 65 and presses the thread end 46 against the bracket 65, holding it firmly during the thread cutting operation by the blades 48 and 49. When the shaft 34 is rotated in the reverse direction to move the binding member 20 into inoperative position, the spring member 66 is swung away from the bracket 65 and thereupon the cut thread end 46 falls to the floor or into a receptacle.

To prevent the thread end 45 extending downwardly from the skein 44 from being acted upon by the cutters 48 and 49, I provide a deflector 70 for pushing aside the thread end 45. The deflector 70 may be composed of bristles or equivalent material held at their rear ends in a socket 71 secured to one edge of the part 52 of the bracket 51. The deflector 70 occupies a position over the cutter blades 48 and 49 and extends in their general direction so that as the arm 25 is swung in the counter-clockwise direction to bring the parts carried by it into operative position, the deflector 70 encounters the thread end 45 and pushes it out of the way, as clearly shown in Fig. 5.

Having thus described the invention what I claim as new is:—

1. In a machine of the character described having means for supporting two skeins connected by a thread, and means for parting the thread to leave a thread end upstanding from the lower skein, means for severing the upstanding thread end relatively close to its skein.

2. In a machine of the character described having means for supporting two skeins connected by a thread, a pivotally mounted arm, means for moving the free end of the arm toward and from the skeins, and means carried by the arm for severing the thread to leave an end upstanding from the lower skein, means carried by the arm for severing the upstanding thread end relatively close to its skein.

3. In a machine of the character described having means for supporting two separated skeins placed one above the other, the lower skein having a thread end extending upwardly therefrom, an arm movable toward

and from the skeins, and means including a vertically arranged, oscillatory shaft carried by the arm for fixing a binder on the upper skein, a pair of shears carried by the 5 arm consisting of a fixed blade and a movable blade, and means connected with the shaft for operating the movable blade to close it upon the fixed blade to sever the upstanding thread end during the binding operation.

10 4. In a machine of the character described having means for supporting a skein with a thread end extending upwardly therefrom, an arm movable toward and from the skein, a vertically arranged, oscillatory shaft 15 mounted on the arm, a pair of cutting blades carried by the arm consisting of a fixed blade and a movable blade, and means connected with the shaft for closing the movable blade upon the fixed blade to sever the upstanding thread end relatively close to the skein when 20 the arm has been moved toward the skein.

25 5. In a machine of the character described having means for supporting a skein with a thread end extending upwardly therefrom, an arm movable toward and from the skein, and a vertically arranged, oscillatory shaft mounted upon the arm, a pair of cutting blades carried by the arm consisting of a fixed 30 blade and a movable blade, a bracket carried by the arm adapted to contact with the upstanding thread end when the arm has been moved toward the skein, flexible thread holding means connected with the shaft for pressing the thread end against the bracket, and 35 means connected with the shaft for operating the movable blade to close it upon the fixed blade to sever the thread end at a point between the skein and the holding means.

40 6. In a machine of the character described having means for supporting two separated skeins placed one above the other, the upper skein having a thread extending toward the lower skein, and the lower skein having a

thread end extending toward the upper skein, a pivotally mounted arm, skein binding 45 means carried by the arm including a vertically arranged, oscillatory shaft, and means for moving the free end of the arm toward and from the skeins, a pair of cutting blades carried by the arm consisting of a fixed blade 50 and a movable blade, means connected with the shaft for actuating the movable blade to close it upon the fixed blade to sever the upstanding thread end relatively close to its skein, and means carried by the arm for engaging and pushing to one side the depending thread end so that it will not be engaged and severed by the blades.

55 7. In a machine of the character described having means for supporting two separated skeins placed one above the other, the upper skein having a thread end extending downwardly toward the lower skein, and the lower skein end having a thread end extending upwardly toward the upper skein, a pivotally 60 mounted arm movable toward and from the skeins, and skein binding means mounted on the arm including a vertically arranged, oscillatory shaft for placing a binder on the upper skein, a pair of cutting blades carried 65 by the arm consisting of a fixed blade and a movable blade, a bracket carried by the arm above the blades adapted to engage one side of the upstanding thread end when the arm is moved toward the skeins, means connected 70 with the shaft for actuating the movable blade to close it upon the fixed blade, thread holding means carried by the shaft for engaging and holding the thread end against 75 the bracket as the movable blade closes upon the fixed blade to sever the thread end, and a brush carried by the arm adapted to engage and push aside the depending thread end as 80 the arm moves toward the skeins.

HENRY WRAY.
